ELECTROMAGNETIC RELAY

Konrad Müller, Berlin-Spandau, Germany, assignor to Siemens & Halske Aktiengesellschaft, Wernerwerk, Siemensstadt, near Berlin, Germany

Application February 25, 1937, Serial No. 127,581
In Germany March 14, 1938

4 Claims. (Cl. 175—345)

The invention relates to electromagnetic relays and especially for those used in telephony and having an angle armature mounted on a knife edge.

5 Relays of this kind are already known in which in order to be able to adjust the release period, the armature is provided with a distance plate instead of a so-called distance pin. If such a 10 distance plate is to be exchanged for another larger or smaller plate in order to vary the release period of the armature then in the known embodiments a corresponding alteration of the travel of the armature was involved and this rendered necessary considerable and therefore undesirable bending of the armature.

The invention relates to an arrangement in which the armature travel remains unaltered independent of the size of the distance plate. According to the invention this is achieved in that 15 the distance plate stretches to the lower edge of the yoke and preferably as far as the edge on which the armature is mounted. By this means on altering the size of the distance plate the point of pivot of the armature is also altered in 20 correspondence with the size of the distance plate since with this arrangement the distance plate constitutes the armature bearing surface as the armature rotates about the upper edge of the yoke which forms the knife edge bearing for the armature. This has the additional effect that the 25 magnetic circuit is not only altered at the pole piece of the armature when a distance piece is exchanged but also at the point of mounting of the armature.

The invention is illustrated in the drawing by way of three embodiments. Only those parts of the relay are shown which are necessary for understanding the invention.

In all the figures the armature 1 is shown in the attracted position. The distance plate 2 in the embodiment shown in Fig. 1 consists of non-magnet material, for example of brass. It is fixed to the armature 1 by one or more screws 3 which at the back of the distance plate engage in a plate 4 and hold this fast against the distance plate. The plate 4 at one of its ends extends close to the pole of the core 5 and its other end extends close to the yoke 7 in order to clamp the distance plate 2 as closely as possible against the surface of the armature 1 above both the pole surface and the bearing edge 6. To increase this effect the distance plate 2 may conveniently be pre-tensioned by bending the plate slightly so that when the clamping plate 4 is screwed up tightly the outer edges of the distance plate will be

exerting pressure against the underside of the armature. The tension plate 4 can consist of magnetic material so that it may serve at the same time for influencing the magnetic lines of force passing between the core and the yoke.

Fig. 2 shows a relay having a distance plate of a different construction. The distance plate used in this case comprises two parts 2a and 2b having different properties. Only the lower portion 2b associated with the pole of the armature 10 is formed of non-magnetic material, the other portion 2a, which forms the surface that engages the knife edge of yoke 7, consisting of iron. Any possibility of influencing the lines of force of the magnetic circuit at this point is thereby prevented. The attachment of the two parts of the distance plate is the same.

Fig. 3 represents a relay in which in addition to the actual distance plate 2 an additional plate 8 is employed. This latter plate, which may consist either of magnetic or non-magnetic material, may be of any thickness desired in order to alter the distance between the armature 1 and the knife edge of yoke 7 and thereby change the travel of the armature.

With this arrangement a simple alteration of the armature travel is made possible by merely exchanging the additional plate 8 while leaving the distance plate.

As may be seen from the foregoing description these arrangements enable adjustments of the air gap and armature travel of a relay of this sort to be made in a simple way.

What is claimed is:

1. In an electromagnetic relay, a pivotal armature, a yoke having a knife edge forming the fulcrum for said armature, a non-magnetic spacer plate on said armature for preventing the armature from contacting the core of said relay and extending along said armature to form the surface that engages the knife edge upon which the armature pivots on said fulcrum, and a retaining plate mounted on said armature between the core of said relay and said yoke for clamping said spacer against said armature.

2. In an electromagnetic relay, a pivotal armature, a yoke having a knife edge forming the fulcrum for said armature, a spacer plate formed in two parts, one of said parts consisting of magnetic material, said plate mounted on said armature so that it prevents the armature from directly contacting the core of said relay and so that the magnetic portion of said plate extends along said armature to form the surface that engages

the knife edge upon which the armature pivots on said fulcrum.

3. In an electromagnetic relay, a pivotal armature, a yoke having a knife edge forming the fulcrum for said armature, a first spacer plate for said armature to prevent the armature from freezing against the core of said relay and extending beyond the knife edge of said fulcrum, a second spacer plate for said armature extending beyond the knife edge of said fulcrum to form the surface that engages the knife edge upon which said armature pivots, and means whereby said second spacer plate can be removed and another spacer plate of different thickness 15 may be substituted therefor to alter the amount of travel of said armature about its pivot point.
4. In an electromagnetic relay, a pivotal armature, a yoke having a knife edge forming the

fulcrum for said armature, a first spacer plate for said armature to prevent the same from freezing against the core of said relay and extending beyond the knife edge of said fulcrum, a second spacer plate on said first plate and extending beyond the knife edge of said fulcrum to form the surface that engages the knife edge upon which said armature pivots, means whereby spacer elements of different thicknesses may be substituted for said spacer elements, the distance of said travel of said armature about said pivot point remaining the same with different thicknesses of said first spacer element, and the distance of travel of said armature about said pivot point being altered with said second spacer 15 element.
